UNITED STATES PATENT OFFICE.

JAMES HAWKINS, OF PHILADELPHIA, PENNSYLVANIA.

DESIGN FOR FISHBONE-TONGS.

SPECIFICATION forming part of Design No. 36,857, dated March 22, 1904.

Application filed February 8, 1904. Serial No. 192,718. Term of patent 3½ years.

To all whom it may concern:

Be it known that I, JAMES HAWKINS, a citizen of the United States, residing at Philadelphia, in the county of Philadelphia and State of Pennsylvania, have invented a new, original, and ornamental Design for Fishbone-Tongs, of which the following is a specification, reference being had to the accompanying drawing, forming part thereof.

What I claim as new, and desire to secure to by Letters Patent, is—

The ornamental design for fishbone-tongs, as shown.

JAMES HAWKINS.
